tion of New York

Filed July 27, 1960, Ser. No. 45,666
12 Claims. (Cl. 204—101)

This invention relates to the preparation of phosphine by the electrolysis of phosphorous.

Heretofore, phosphine has been prepared by the reaction of metallic phosphides or phosphonium halides with water, and by the hydrolysis of elemental phosphorous. These methods have been unsatisfactory because of the high production costs and/or because the phosphine product is in an impure form.

United States Patent No. 1,375,819, issued April 26, 1921, to Henry Blumenberg, Jr., discloses a method for preparing arsine by the electrolysis of a salt or oxide of arsenic in the presence of sulfuric acid and potassium sulfate or other compounds capable of liberating nascent hydrogen upon electrolysis. However, phosphine is not produced under the conditions set forth by Blumenberg when an oxide or salt of phosphorous is employed.

W. R. Grove, in the Journal of the Chemical Society, vol. 16 (1863), pp. 263-272, discloses the use of an electric current to boil moist molten phosphorous and produces phosphine thereby. Such a technique requires a high voltage, and converts only a small amount of phosphorous to phosphine.

It is an object of this invention to provide a method of producing phosphine by electrolytic means.

Another object of the invention is to provide a more economical method of producing phosphine.

Still another object of the invention is to provide a method of producing phosphine in a form substantially free from lower phosphorus hydrides and other phosphorus impurities.

These and other objects of the invention will be apparent from the following detailed description of the invention.

It has now been discovered that phosphine can be prepared by passing an electric current between an anode and a liquid cathode in contact with an electrolyte, the cathode also being in agitated contact with molten phosphorous. Sufficient agitation should be provided for the liquid cathode and molten phosphorous to permit the current to flow between the cathode and the anode.

The accompanying drawing is a schematic illustration of a suitable electrolytic cell for carrying out the novel process. Referring to the drawing, there is shown cell vessel 10, having a cathode section 11, and an anode section 12, the sections being separated by a porous diaphragm 13. A gas-tight anode section cover 14 having ports 15, 16 and 17, is secured to the top of the cell vessel 10.

Extending through port 15 is anode 18, which is positioned in anode section 12. Anode 18 is shown in the drawing as a cylinder, but any suitable shape may be employed. Cathode section 11 extends through port 16 into anode section 12 to a point adjacent to, but removed from the bottom of cell vessel 10. A gas-tight cathode section cover 38 having ports 19, 20, 21, 22 and 23 is secured to the top of the cathode section 11. A liquid cathode 24 is placed in the bottom of cathode section 11, up to the level indicated by interface 25. Molten phosphorus 26 is placed in the cathode section 11 up to the level indicated by interface 27. An aqueous electrolyte 28 fills the anode and cathode sections up to the level indicated by interface 29.

Cathode conductor 30 which is covered with a suitable insulating material 39, such as glass, extends from molten

2

cathode 24 through port 19 to the negative pole of a source of electrical energy 31. Electric conductor 32 connects anode 18 with the positive pole of electrical energy source 31.

Motor driven agitation means 33 extends through port 20 into the liquid cathode. This type of agitating means is shown to demonstrate the preferred means for agitating the liquid cathode and molten phosphorus in a cell of this design, but any suitable type of agitating means may be employed.

When an electric current is passed between the cathode and the anode, a gaseous mixture comprised of phosphine and hydrogen is discharged at the cathode and passes out the cathode section through catholyte gas discharge outlet 34, which extends to the exterior of the cell through port 21. The gas produced in the anode section passes out through anolyte gas discharge outlet 35, which extends through port 17.

Funnel 36, which extends through port 23, is provided for the addition of electrolyte and/or molten phosphorus to the cathode section 11.

A thermometer 37, or other suitable temperature measuring means, extends through port 22 into the electrolyte contained in cathode section 11.

It will be recognized by those skilled in the art that the design of the electrolytic cell shown in the drawing can be modified without departing from the spirit of the invention. For example, the position of the anode section and the cathode section can be reversed, wherein liquid cathode and molten phosphorus are placed in the bottom of the cell vessel 10. In such a cell, the agitating means 33 is positioned in the bottom of cell vessel 10.

Regardless of the type of cell employed, it is important that sufficient agitation be imparted to the liquid cathode and the molten phosphorus to permit the flow of current between the cathode and the anode.

Cell vessel 10 may be constructed of glass, ceramics, rubber-lined steel, or other suitable impervious materials.

Porous diaphragm 13 may be construed of porous alundum, sintered glass, plastic cloth, glass cloth, or other porous materials, such as ion-exchange membranes and the like.

Molten white phosphorous, sometimes referred to as yellow phosphorous, is preferably employed as the source of phosphorus for the phosphine product, but other allotropic forms of phosphorus may be employed if desired. The temperature of the phosphorous should be sufficient to maintain it in a molten state, without effecting boiling thereof. For this reason, the temperature of the molten phosphorus and electrolyte is maintained within the range between about forty-four degrees and about two hundred and eighty degrees centigrade, and preferably between about fifty and about one hundred and twenty degrees centigrade. Temperature control of the phosphorous and the electrolyte is readily obtained by means of a constant temperature bath (not shown in the drawing), but any suitable temperature control means may be employed. For example, on start-up of the electrolytic process, the molten phosphorous and electrolyte may be heated to a temperature within the aforesaid temperature range by means of an external source of heat, and maintained at this temperature by means of a constant temperature bath.

Any cathodic material which is liquid under the aforesaid conditions may be employed as a cathode in the instant novel process. Suitable cathodes include mercury, gallium, and alloys of bismuth, cadmium, tin, and lead, which are liquid under the aforesaid temperature conditions. An example of a suitable alloy is Wood's metal, a material containing fifty percent bismuth, twenty-five percent lead, twelve and one-half percent tin, and twelve and one-half percent cadmium. This alloy melts at a temperature above about seventy degrees centigrade.

However, any alloy or other material capable of acting as a cathode, while in liquid form under the aforesaid temperature conditions, can be employed.

Suitable anode materials include lead, lead-antimony, lead dioxide, platinum, graphite and stainless steel.

Any electrolyte which is non-reactive with molten phosphorus, and which is capable of forming hydrogen ions under the electrolysis conditions employed, may be employed as the electrolyte. Suitable electrolytes include aqueous solutions of phosphoric acid, sulfuric acid, hydrochloric acid, sodium chloride, lithium chloride, sodium sulfate, potassium chloride, potassium sulfate, monosodium phosphate, disodium phosphate, monopotassium phosphate, dipotassium phosphate, and mixtures thereof. An aqueous phosphoric acid solution containing between about ten and about eighty, and preferably between about fifteen and about fifty percent phosphoric acid by weight, is preferably employed as the electrolyte, but other concentrations may be employed if desired. Concentration of the aqueous solutions of the aforesaid acids, when employed as an electrolyte, should be equivalent to the aforesaid phosphoric acid concentrations. Aqueous solutions of the aforesaid salts having a concentration between about ten percent by weight and the concentration sufficient to produce a saturated solution under the temperature conditions obtained, may be used.

If phosphoric acid, sulfuric acid, or salts of these acids are employed as the electrolyte, the anolyte gas predominates in oxygen, when other than graphite is employed as the anode. If those acids and/or salts are employed as the electrolyte, and the anode is constructed of graphite, the anolyte gas will predominate in carbon dioxide.

Control of the current and current density during electrolysis is important. The current should be maintained at at least one ampere or above, preferably as high as possible without increasing the voltage above about twenty volts. Current density is preferably maintained as high as possible, consistent with a reasonable level of phosphine production. Commercially acceptable phosphine production rates can be attained when the cathodic current density is maintained at at least about five amperes per square foot and preferably between about ten and about seven hundred amperes per square foot. However, it will be recognized by those skilled in the art that optimum current and optimum current density will vary with the particular cell design employed.

The gas produced at the cathode in accordance with the instant novel process is a mixture of phosphine and hydrogen, containing as high as ninety percent phosphine or higher. When an acid is used as the electrolyte, the resulting catholyte gas is substantially free from phosphorus hydride impurities. As a result when the catholyte gas is employed as a chemical intermediate, the product of the reaction is in a highly pure form. For example, tetrakis(hydroxymethyl) phosphonium chloride is prepared by the reaction of phosphine, formaldehyde, and concentrated hydrochloric acid. When phosphine prepared by the conventional process is employed to produce tetrakis(hydroxymethyl) phosphonium chloride, the resulting product has a purity of about ninety-six point five percent. In contrast, when phosphine prepared in accordance with the instant novel process is used to prepare tetrakis(hydroxymethyl) phosphonium chloride, the purity of the product is as high as ninety-nine point nine percent.

An important advantage in preparing phosphine in accordance with the instant novel process, is that the gas is free from other phosphorus hydrides, and therefore, is not spontaneously flammable when in contact with air.

The following examples are presented to define the invention more clearly without any intention of being limited thereby. All parts and percentages are by weight unless otherwise specified.

Example 1

A cell of the design shown in the drawing was used to prepare phosphine. The cell vessel was a two-liter glass beaker, and the cathode section was a porous alundum cylinder, having an inside diameter of three inches, and a volume of about seven hundred milliliters. The porous alundum served as the diaphragm. The anode was a lead cylinder having an inside diameter of three and five-eighths inches, and a height of three and one-half inches. The lead cylindrical anode was perforated with one-eighth inch diameter holes.

Thirty-five milliliters of mercury and twenty grams of molten white phosphorus were placed in the cathode section. About sixteen hundred milliliters of aqueous eighteen percent phosphoric acid were added to the cathode and anode sections. A current of 2.1 amperes and a voltage of seven volts were impressed upon the system during the electrolysis. No stirring of the molten phosphorus and mercury was employed in this test. The temperature of the molten phosphorus and electrolyte was maintained at about seventy-seven degrees centigrade. A gaseous mixture of phosphine and hydrogen, having a concentration of twenty percent phosphine by volume was produced at the cathode at the rate of 13.5 milliliters per minute.

Example 2

The procedure of Example 1, employing the cell of Example 1, was repeated with the exceptions noted hereinafter. Fifty milliliters of mercury and thirty-five grams of molten white phosphorus were added to the cathode section. An aqueous forty percent phosphoric acid solution was employed as the electrolyte. A current of five amperes and a voltage of 5.3 volts were impressed on the system during electrolysis. The temperature of the electrolyte and molten phosphorus were maintained at a temperature about eighty-five degrees centigrade, by placing the cell vessel in a constant temperature bath.

The liquids in the cathode chamber were vigorously agitated during electrolysis, so that the mercury cathode contacted the electrolyte as well as the molten phosphorus.

A gaseous mixture of hydrogen and phosphine was produced at the cathode at the rate of 26.2 milliliters per minute and had a phosphine concentration of 85.5 percent by volume.

Example 3

The procedure of Example 2 was repeated with the exceptions noted hereinafter. The anode was the lead cylinder employed in Example 2, having a three-eighths inch graphite rod connected thereto. Fifty milliliters of mercury and thirty grams of molten phosphorus were added to the cathode section. A current of two amperes and a voltage of four volts were impressed on the system during the electrolysis.

A gaseous mixture of phosphine and hydrogen was produced at the cathode at the rate of 10.5 milliliters per minute, and had a phosphine concentration of 83.5 percent by volume.

Example 4

An electrolytic cell similar in design to that shown in the drawing was employed in this example, with the exceptions noted hereinafter. A five hundred milliliter glass beaker was employed as the cell vessel. The position of the cathode and anode sections was reversed. The anode section was a porous sintered glass cylinder having a volume of about fifty milliliters. A three-eighths of an inch diameter by six inch long graphite rod was employed as the anode and inserted into the porous sintered glass cylinder. A Wood's metal disk about one-quarter of an inch thick and about three inches in diameter was placed in the bottom of the cell vessel, and thirty grams of mol-

ten white phosphorus were added thereto. No agitation was provided in the anode section, but agitation in the cathode section was effected by means of a magnetic stirrer.

The electrolyte and molten phosphorus were heated to a temperature of eighty-five degrees centigrade, whereby the metal disk melted. A copper wire was inserted into the bottom of the cathode section to contact the liquid metal cathode and connect it with the source of direct current.

A current of one ampere and a voltage of seven volts was impressed upon the system during electrolysis. The temperature of the electrolyte, molten phosphorus and liquid alloy cathode was maintained at eight-five degrees centigrade during electrolysis by means of a constant temperature bath.

The gaseous mixture of phosphine and hydrogen produced at the cathode had a concentration of 92.5 percent phosphine by volume, and was produced at the rate of 7.3 milliliters per minute.

Example 5

The procedure of Example 4 was repeated, employing the cell of Example 4, with the exceptions noted herein-after. Fifty milliliters of mercury were added to the cathode section of the cell vessel to serve as a cathode instead of the Wood's metal. A current of one-half ampere and a voltage of eight volts were impressed upon the system during electrolysis. A temperature of ninety degrees centigrade was maintained in the cathode section.

The gaseous mixture of phosphine and hydrogen produced at the cathode contained ninety-five percent phosphine by volume and was produced at the rate of 2.7 milliliters per minute.

It will be recognized by those skilled in the art that various modifications within the invention are possible, some of which have been referred to above. Therefore, I do not wish to be limited except as defined by the appended claims.

I claim:

1. The process for the production of phosphine which comprises passing an electric current between an anode and a liquid cathode in contact with an aqueous electrolyte to yield a cathodic current density of at least about five amperes per square foot, said cathode being in contact with molten phosphorus, whereby phosphine is produced at the cathode.
2. The process of claim 1 wherein said cathode is in agitated contact with said molten phosphorus.
3. The process of claim 1 wherein said cathode is mercury.
4. The process of claim 1 wherein said cathode is a liquid alloy of bismuth, lead, tin and cadmium.
5. The process of claim 1 wherein said electrolyte is

capable of forming hydrogen ions under the electrolysis conditions employed and is non-reactive with molten phosphorus.

5 6. The process of claim 1 wherein said electrolyte is phosphoric acid.

7. The process of claim 1 wherein said electrolyte is an aqueous phosphoric acid solution containing between about ten and about eighty percent phosphoric acid by weight.

10 8. The process of claim 1 wherein the temperature of the electrolyte and molten phosphorus is maintained during electrolysis within the range between about forty-four and about two hundred and eighty degree centigrade.

15 9. The process of claim 1 wherein the temperature of the electrolyte and molten phosphorus is maintained during electrolysis within the range between about fifty and about one hundred and twenty degrees centigrade.

10 10. The process of claim 1 wherein the current density of said cathode during electrolysis is maintained in the range between about ten and about seven hundred amperes per square foot.

15 11. The process of claim 10 wherein the voltage during electrolysis is maintained below about twenty volts.

20 12. The process for preparing phosphine which comprises passing an electric current between an anode and a mercury cathode in contact with an aqueous phosphoric acid solution electrolyte, a portion of said electrolyte in contact with said mercury cathode being admixed with molten phosphorus, said molten phosphorus being in agitated contact with said cathode, and maintaining a current density on said mercury cathode of at least about five amperes per square foot, whereby a phosphine-containing gas is produced at the cathode.
